US0D1112223S

(12) **United States Design Patent** (10) Patent No.: **US D1,112,223 S**
(45) Date of Patent: ** Feb. 10, 2026

(54) **DONGLE**

(71) Applicant: **Arlo Technologies, Inc.**, Carlsbad, CA (US)

(72) Inventors: **Scott McManigal**, Newport Beach, CA (US); **Soo Youn Park**, Lake Forest, CA (US); **Christopher Fonzo**, Carlsbad, CA (US)

(73) Assignee: **Arlo Technologies, Inc.**, Carlsbad, CA (US)

(**) Term: **15 Years**

(21) Appl. No.: **29/925,490**

(22) Filed: **Jan. 24, 2024**

(51) LOC (15) Cl. **14-02**

(52) U.S. Cl.

USPC **D14/433**

(57) **CLAIM**

The ornamental design for a dongle as shown and described.

DESCRIPTION

FIG. 1 is a top, front, right side perspective view of a dongle showing our design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a top, rear, right side perspective view thereof.

The dash-dash broken lines shown in the figures depict portions of the dongle that form no part of the claimed design. The dash-dot broken lines depict the boundaries of the claimed design and form no part thereof.

1 Claim, 7 Drawing Sheets
